WINDOW AND PANEL COMBINATION FOR A PREFABRICATED HOUSE

David C. Seman, 638 Brown Ave.; Colman J. Seman,
1409 Springlake Drive; and Fredrick P. Seman, 1034
Montpelier Ave., all of Erie, Pa.; and John G. Seman,
E. Main Road, North East, Pa.

Filed Mar. 8, 1962, Ser. No. 69,142

Term of patent 14 years

(Cl. D13—1)

The figure of the drawing is an isometric view of a window and panel combination for a prefabricated house, showing our new design. The rear side of the panel is plain and the rear of the window is like the front shown.

We claim:

The ornamental design for a window and panel combination for a prefabricated house, as shown and described.
